FUSE FOR PROJECTILES

Marvin L. Mathsen, Rockaway, N. J.

Application June 4, 1934, Serial No. 728,916

3 Claims. (Cl. 102—39)

(Granted under the act of March 3, 1883, as amended April 30, 1928; 370 O. G. 757)

The invention described herein may be manufactured and used by or for the Government for governmental purposes, without the payment to me of any royalty thereon.

5 This invention relates to a fuse for projectiles. The principal object of the invention is to provide a bore-safe fuse in which a pair of relatively movable members are connected by linkage which function during flight to move one of the members to unarmed position and to hold it in such position until impact.

10 A further object is to associate one of said members with a mask whereby the mask cannot be removed until the fuse is in flight. Another object is to provide a striker and firing pin with a bore-safe device.

15 With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

20 A practical embodiment of the invention is illustrated in the accompanying drawing, wherein:

Fig. 1 is a longitudinal sectional view of a fuse constructed in accordance with the invention and showing the parts in normal position.

25 Fig. 2 is a fragmentary sectional view showing the parts in position during flight.

Fig. 3 is a similar view of a modification.

30 Fig. 4 is a longitudinal sectional view of a further modification.

Referring to Figs. 1 and 2 the fuse comprises a casing formed by a body 5 threadedly connected to a base 6 and a nose 7.

35 The base carries the usual booster charge 8, detonator 9 and houses a conventional rotor 10 mounted on a pivot pin 11. When the rotor is in armed position, a primer 12 carried thereby is positioned axially of the fuse and in line with the detonator.

40 The rotor is normally held in the unarmed position, masking the detonator by means of a transversely disposed bolt 13 adapted to be withdrawn from engagement with the rotor due to the action of centrifugal force and it is also held against rotation by the point 14 of a firing pin which is disposed in a blind cavity 15 in the rotor.

45 A firing pin 16 and a striker 17 are positioned axially of the fuse casing and are arranged with their adjoining ends interfitted. Specifically, 50 the lower end 18 of the striker is provided with a

socket 19 for receiving the reduced upper end 20 of the firing pin. A spring 21 in the socket normally urges the firing pin and striker apart and maintains the point 14 of the firing pin in the blind cavity 15 of the rotor.

5 The firing pin and striker are connected by a plurality of sets of linkages, each consisting of a pair of links 22 and 23, respectively attached to the firing pin and striker by pivot pins 24 and 25 and linked to one another by a pivot pin 26. The 10 adjoining end portions of the links carry weights 27.

The lower end 28 of the firing pin enters a counterbored aperture 29 in a plate 30 closing the rear end of the body 5. It engages a shoulder 31 which serves to limit its downward movement under the action of the spring 21.

20 For convenience in manufacture and assembling the striker 17 includes a front part 17^a which protrudes from the nose 7 of the casing. A pin 32 in the nose 7 enters a longitudinally extending groove 33 in the part 17^a and restrains the striker against rotational displacement. A spring 34 surrounding the striker 17 is seated on the neck 35 of the body 5 and acts on the part 17^a to maintain it in protruding position relative to the nose. A sleeve 36 surrounding the spring 34 holds it against excessive lateral displacement.

25 In the modification shown in Fig. 3 the firing pin 37 is adapted to directly engage the rotor 38 which moves to unmasking position during flight and need not be provided with a primer.

30 In the modification shown in Fig. 4 the striker 39 is in one piece and the firing pin 40 enters an aperture 41 in the base 42 of the fuse casing. It 35 directly engages a transversely movable slide 43 which masks the primer-detonator 44.

35 The operation of the fuse shown in Figs. 1 and 2 is as follows: When a projectile equipped with the fuse is fired from a gun and rotates in flight, 40 the parts assume the positions shown in Fig. 2. The bolt 13 is moved by centrifugal force out of engagement with the rotor and the adjoining ends of the links 22 and 23, moving outward under the influence of centrifugal force, withdraw 45 the firing pin from the rotor. The rotor, being now free, turns under the action of centrifugal force and positions the primer 12 in line with the detonator 9 and the point 14 of the firing pin.

40 On impact the striker and the firing pin are 50 driven rearwardly to actuate the primer. In the event of ricochet and failure of the striker to be driven rearwardly, the spring 21 will drive the firing pin into the primer when the links are no longer under the influence of centrifugal force. 55

I claim.

1. In a fuse, a casing, an explosive unit in the casing, a member masking the explosive unit and mounted for movement to unmasking position, a striker having its front end passing through the nose of the casing and having a socket in its rear end, a spring normally holding the striker in forward position with its front end protruding from the casing, a firing pin having its front end disposed in the socket of the striker, a spring confined between the striker and firing pin and normally urging the firing pin rearwardly into the path of movement of the masking member and linkages connecting the striker and firing pin and operable by centrifugal force to withdraw the firing pin from the path of movement of the masking member.
- 10 2. In a fuse, a casing, an explosive unit in the casing, a member masking the explosive unit and

mounted for movement to unmasking position, a striker having its front end passing through the nose of the casing, a spring normally holding the striker in forward position with its front end protruding from the casing, a firing pin in line with the striker, a spring confined between the striker and firing pin and normally urging the firing pin rearwardly into the path of movement of the masking member and linkages connecting the striker and firing pin and operable by centrifugal force to withdraw the firing pin from the path of movement of the masking member. 5

15 3. In a fuse, a striker, a firing pin coaxial with the striker, a spring normally urging the striker and firing pin apart, and linkages connecting the striker and firing pin and operable by centrifugal force during flight of the fuse to relatively move the striker and firing pin towards one another.

MARVIN L. MATHSEN.
